INVENTOR.
Manley A. Sparks,
BY
John B. Brady
ATTORNEY.

UNITED STATES PATENT OFFICE.

MANLEY A. SPARKS, OF ATLANTA, GEORGIA.

DENTAL APPARATUS.

Application filed April 9, 1927. Serial No. 182,495.

My invention relates broadly to dental apparatus and more particularly to a plaster trimmer for use in the shaping of patterns in the preparation of dentures.

- 5 One of the objects of my invention is to provide a construction of cutter for working various grades of plaster some of which become very hard after setting wherein the model being operated upon may be supported upon an angularly disposed desk-like platform upon which the pattern may be moved to various positions beneath a co-operating plaster cutter and readily shaped to the desired size.
- 10 Another object of my invention is to provide a construction of plaster trimmer and cooperating tray whereby all particles which are moved from the model being operated upon may be retained in the tray and removed from the trimmer, the tray remaining in a horizontal position at all times.

Still another object of my invention is to provide a construction of cutter arranged to be mounted upon a plaster trimmer table where the pattern may be disposed at a substantial angle to the horizontal during the trimming operation and whereby considerable force may be applied to the cutting operation of the trimmer with a positive stop arranged to limit the movement of the cutting blade.

A further object of my invention is to provide a construction of combined plaster trimmer and tray wherein an interlocking and spring pressed connection may be effected between the tray and the plaster trimmer, the tray connecting with one side of the plaster trimmer by means of interlocking lugs and a spring engagement device by which the tray may be automatically snapped into and retained in position with respect to the trimmer and readily removed therefrom for dispensing the particles which may be cut from the pattern which is being shaped.

Other and further objects of my invention reside in the construction and arrangement of parts of the plaster trimmer as will be more fully set forth in the specification hereinafter following by reference to the accompanying drawing in which:

Figure 1 is a plan view showing the plaster trimmer and tray attached thereto; Fig 2 is a side elevation showing the combined plaster trimmer and tray; Fig. 3 is

a cross-sectional view through the plaster trimmer and tray taken on line 3—3 of Fig. 2; Fig. 4 is a fragmentary plan view of the tray locked into position with respect to the plaster trimmer; Fig. 5 is a fragmentary view of the plaster tray about to be removed from the plaster trimmer; Fig. 6 is a view of the plaster tray removed longitudinally with respect to the frame of the plaster trimmer about to be withdrawn laterally away from the plaster trimmer; Fig. 7 is a fragmentary cross-sectional view on line 7—7 of Fig. 5 showing the plaster tray in its process of removal from the plaster trimmer; and Fig. 8 is a perspective view illustrating the tray and showing the upstanding lugs by which the removable connection is established with the plaster trimmer.

Heretofore in the practice of dentistry it has been customary to shape the patterns in forming dentures by the use of hand tools and a sharp blade has been necessary in this work, and by reason of the hardness of the plaster with which it is necessary to work, considerable force must be applied to the blade. Such hand tools have proven very dangerous and have resulted in bad knife wounds due to the slipping of the knife under heavy pressure. I have devised the present plaster trimmer for eliminating the danger of slippage of a knife in the shaping of the plaster pattern and at the same time provided means for securing the necessary pressure under which a blade must be moved with respect to the plaster pattern for shaping the pattern. The plaster on which the trimmer of my invention operates is known as synthetic stone or artificial stone, which material becomes very hard and difficult to work.

With the arrangement of the desk-like platform in the plaster trimmer of my invention, however, the plaster patterns may be moved about to selected positions and pressure applied to the cutting knife for shaping the plaster pattern to desired size. The excess plaster which is trimmed from the model is deposited in a movable tray adjacent the trimmer. This tray is locked with respect to the trimmer by a spring device which enables the tray to move both longitudinally and laterally with respect to the trimmer for establishing a close interlocking fit therewith, insuring the deposit of

all the trimmed material into the tray. The tray is so shaped with respect to the frame of the trimmer that the tray fits beneath the trimmer and thereby receives all of the excess material. The spring device constantly urges the tray into more intimate interlocking relationship with the trimmer, as will be more fully hereinafter described.

Referring to the drawings in more detail, 10 reference character 1 designates the base of the trimmer which is provided with an angularly disposed desk-like surface 2 for receiving the model or pattern which is being operated upon. The base 1 has an upstanding supporting member 3 thereon to which is journaled as represented at 4 the lever knife 5. The lever is shaped as represented in Fig. 2, providing a relatively wide body portion 6, having a pair of guides 7 and 8 thereon, between which the cutting blade 9 is positioned. The cutting blade 9 is adjustable by means of screw device 10 operating in slots 11. The base 1 has a shortened edge portion as represented at 12, the 15 edge portion 12 being provided with a pair of vertically extending apertures 14 and 15 which are arranged to cooperate with upstanding lug members 16 and 17 on the tray 18. The tray 18 is more clearly represented 20 in Fig. 8 as having relatively high upstanding sides 19 tapering to the low side portions 20 and 21. The side portion 21 is sufficiently low to pass beneath the lower edge 12 of the plaster trimmer body 1. It becomes highly 25 desirable to eliminate the tipping of the tray when attaching tray to the trimmer or removing the tray from the trimmer. This is accomplished by the arrangement illustrated in the drawing where a spring device 30 22 is provided attached to one corner of the tray 18 with a resilient portion 23 arranged to engage the side of the trimmer 1. When interlocking the tray with the trimmer as illustrated in Fig. 6 the tray has the upstanding lugs 16 and 17 aligned with the 35 apertures 15 and 14. The tray is passed forward toward the trimmer in such manner that the lugs 16 and 17 pass wholly through the apertures 15 and 14, the spring device 40 22 being subjected to compressional forces. The tray is then moved longitudinally with respect to the trimmer in such manner that the lugs abut with the corner surface of one wall of the plaster trimmer as illustrated in Fig. 7 until a position is reached as illustrated in Fig. 4 wherein the end of the spring 23 tends to force the tray continuously into tight engagement with the walls of the trimmer by a resolution of both longitudinally and laterally extending forces. Removal of the tray may be effected by a reversal of the hereinbefore described process as represented by the arrow in Fig. 5. By reason of the fact that the tray 18 extends beneath the plaster trimmer there is

no possibility of the cuttings falling outside of the tray. The tray may be removed without tipping so that loss of the particles in the tray due to the low sides 20 and 21 is avoided.

76

The plaster trimmer may be formed with a removable edge portion 24 for cooperation with the removable blade 9. The frame of the trimmer is so shaped as to avoid deep corners, crevices and other places where 75 dust or moisture might accumulate.

For the purpose of facilitating work on plaster models, I have found that a 30° angle is desirable for the desk-like surface 2, the surface being angularly disposed toward the 80 operator. It will be observed that the cutter blade 9 is relatively narrow and is positioned at approximately the center of the length of the operating handle 25 for enabling the desired pressure to be placed upon the knife 85 during the cutting operation.

The plaster trimmer of my invention has proven to be highly practical in operation, and while I have described the invention in one of its preferred embodiments, I desire it 90 to be understood that modifications may be made and that no limitations upon my invention are intended other than are imposed by the scope of the appended claims.

What I claim as new and desire to secure 95 by Letters Patent of the United States is as follows:

1. Dental apparatus comprising a plaster trimmer having a supporting body portion, a tray arranged to be brought adjacent the supporting body portion of said plaster trimmer, and means for interlocking said tray with the supporting body portion of said plaster trimmer, said means comprising a pair of upstanding lugs arranged to engage one side of the supporting body portion of said plaster trimmer, and spring means for forcing said lugs into engagement with the supporting body portion of said plaster trimmer.

105

2. Dental apparatus comprising a plaster trimmer having an inclined desk-like supporting surface, a cutting knife pivotally mounted adjacent the uppermost extremity of said supporting surface and adjacent one side thereof, a tray arranged to be moved in a horizontal direction for interlocking engagement with the side of said supporting surface, and spring means for maintaining said tray in interlocking relationship with 115 said plaster trimmer.

3. Dental apparatus comprising a supporting member having an angularly disposed supporting surface, a cutting knife journaled from a position adjacent the upper extremity 125 of said supporting surface, the side of said supporting member being shortened to permit the horizontal movement of one side of a tray member thereunder, said tray member being provided with upstanding lugs on the 130

side thereof which is adapted to be moved beneath the said side of said plaster trimmer, said plaster trimmer being apertured to permit the interlocking relationship of said lugs with the said side of said plaster trimmer.

4. A dental apparatus comprising a plaster trimmer including a support, a desk-like working surface angularly disposed on said support, a pivotally mounted cutter mounted at one side of said support for cooperation with said working surface, said support terminating immediately below said cutter above the lowermost extremity of said plaster trimmer, a tray having two relatively low sides and a rear relatively high side, with the fourth side thereof tapering from said rear high side to the opposite low side, upstanding lugs on the low side of said tray which is arranged to fit under said plaster trimmer, said plaster trimmer being aper-

tured to permit the interlocking engagement with the lugs on said tray.

5. Dental apparatus comprising a plaster trimmer including a supporting member, an angularly disposed working surface carried by said supporting member, a pivotally mounted cutter positioned at one side of said supporting member for cooperation with said working surface, said supporting member being cut away below said cutter, and a tray having one side thereof shaped to be moved horizontally beneath said supporting member to an overlapping position with respect to the cut away side of the said supporting member, and spring means carried by said tray for establishing an interlocking relation between said tray and said trimmer.

In testimony whereof I affix my signature.

MANLEY A. SPARKS.
